UNITED STATES PATENT OFFICE

ALBERT E. F. MOONE, OF CHICAGO, ILLINOIS

SHINGLE MIXING MACHINE

Application filed March 31, 1930. Serial No. 440,608.

It is frequently desirable to make patterns upon roofs by causing shingles of contrasting colors to appear in some regular order, while on others it is desirable so to break up the 5 color or surfaces, or change the shapes as to prevent any regularity in pattern of color or design.

The purpose of my machine is so to place shingles in the bundle or bale that the above 10 results are achieved automatically, and, accordingly, to minimize the degree of manual handling which is required under present methods.

It is my purpose also to provide a machine 15 which is capable of mixing shingles of similar characteristics but of different color or surface or shape, and stacking them into bundles, so that when the shingles are taken from the bundle in sequence and laid upon a roof, variegations in color, entire non-uniformity, or definite patterns are assured.

I find it also convenient to design the machine in a portable form so that it may be carried to shingle stacks in the warehouse 20 or mixing floor, obviating the necessity for transporting shingles about the plant.

These and other objects of the invention will become apparent from the following disclosure and the accompanying drawings, in 25 which

Fig. 1 is a plan view of my improved shingle mixing device with duplicated sections omitted;

Fig. 2 is an elevation of the device, omitting the same sections as does Fig. 1;

Fig. 3 is a detail elevation of the table elevating mechanism, the shingle carrier, the take-off and throw-over apparatus which deposits material on a roller conveyor;

Fig. 4 is a sectional elevation through one of the mixing units;

Fig. 5 is a detail elevation of the table raising and lowering structure; and

Fig. 6 illustrates an asphaltic shingle such as is used in conjunction with the device.

The machine comprises five organizations. Briefly the organizations are as follows:

1. Apparatus and means for forcing the individual shingles out of the separate uniform stacks.

2. Apparatus and means for determining what, how many and when the shingles shall be forced out from the separate stacks.

3. Apparatus for carrying the shingles away after their delivery from the individual stacks, for maintaining the sequence of such delivery.

4. Apparatus for stacking the shingles in bundles in the sequence as delivered by the carrier.

5. Apparatus to prevent the somewhat sticky asphalt shingles from sticking and jamming.

Each of these functions performed by the five organizations bears a timed and sequential relation to the others.

It is to be understood that the machine may handle sheet material of any description, and accordingly the word "shingle" will be used throughout this specification to indicate such sheet material generically and is not confined to the conventional roofing element of the name.

With reference to Fig. 2, the apparatus comprises a base 11, mounted upon any necessary number of casters 10 and a table-like structure 12 supporting the various sub-assemblies and the longitudinal shaft 13, which is the main driving means. Mounted upon the base 11 is a driving motor 14, delivering power to a double sprocket 15 through the double chains 16, 16 (Fig. 1).

The structure 12 supports an outrigger 17, upon which are supported pillow blocks 18, 19, 20, etc., providing bearing for the main shaft 13. Supported by the structure 12 is a series of slotted tables 21, 21, etc. It is to be understood that two elements only of the machine are shown and described. The other shingle releasing mechanisms are duplicates of those described, and may exist in any number which the pattern to be produced, or the number of colors to be mixed, demands. In the case of the specific machine disclosed in the invention there are five such units.

The shingles to be mixed are placed in the form of stacks on tables 21. Such stacks are indicated at 22, 22. The shingles are held in position against forward displacement (to the left with reference to Fig. 2) by stop as

semblies 23, 23, carried by the structure 12. The assemblies, as shown in Fig. 4, comprise a series of flat bars 24, 25, 26 and 27, making a rectangular frame with braces 28, 28, also attached to the part 12. From the bar 25 hang a plurality of stop members 29, which are hinged at 31, 31. The bar 27 is pierced to allow bolts 32, rigidly attached to the stop members 29, 29, to pass through. The bolts 10 are provided with springs 33, working against the bar 27 and the cap of the bolt. The stop member 29, therefore, is normally pulled into engagement with the bar 27. The stops may be regulated for height by means 15 of the adjusting screws 34, 34.

The main drive shaft 13 is provided at 44, 44, with bevel pinions which mesh with driven bevel gears 45, 45, mounted upon the transverse shafts 46, 46 (best shown in Fig. 20 4). The shafts 46 carry a series of sprockets 47, 47, etc., over which small carrier chains 48, 48, run, which work over sprockets 49, 49, rearwardly positioned behind the stack of shingles. Each of the carrier chain 25 sprockets 49 is individually adjustable for tension upon the chain, as shown in Fig. 3. As indicated in Fig. 3, the sprockets 49 are carried on a bracket 51, slideable upon one of the components of the support 12, and adjustable for tension by means of the cap 30 screw 52 and the locking means provided.

Each of the chains 48 carries a small engaging block 53, projecting upward through the slots provided in the table 21, the purpose 35 of the blocks 53 being to engage the rear edge of one or more of the shingles 22. Two of such blocks are positioned in the whole length of the chain, so that two shingles are engaged and ejected for each complete revolution of the chain. The hinged 40 stop members 29 prevent the whole stack of shingles from moving ahead when the chains force the engaging blocks 53 into contact with the shingle. The height of the stop 29, however, is adjusted to allow one, two or 45 three shingles to pass out below it. Such is the mechanism for forcing shingles out of the stack.

The mechanism determining when and 50 how many shingles are to be released is as follows:—The table 21 is raised or lowered automatically. Two brackets 54 and 55 are provided with slotted ends in which cap screws or rivets 56, 56, rigidly attached to 55 the table 21, are free to move in a vertical direction only. The table is supported by connecting link members 57, 58, in which turn buckles 59, 61, are provided to allow initial leveling of the table. The lower extremities of the link members 57, 58, are connected to bell cranks 62, 63, carried by cross shafts 64, 65. The bell cranks are connected by an intermediate link 66 in such a way that when the shaft 64 is revolved in a clockwise 60 direction the shaft 65 will revolve in a coun-

terclockwise direction and the table 21 will rise to a degree determined by the angle through which the shaft 64 is rotated.

Below each of the shingle units are located cams 67, 67, carried by cross shafts 68. The 70 cams are carried on the faces of large sprockets 69, also mounted upon the same shaft. The contour of the cams 67 may be changed by the insertion of blocks 60, 70, etc. Each block occupies one-fifth of the circumference of the cam and determines the elevation of the roller 72. The arm 71, projecting from the shaft 64 and rigidly attached thereto, carries the roller 72 at its further extremity, which engages with the face of the 75 cam 67 in such a way that upon the rotation of the cam the shaft is caused to revolve clockwise and counterclockwise through a part of one revolution.

For the purpose of providing drives to the cams and for assuring the proper timed relation for the cooperation of the parts, the shafts 46 carry small sprockets 73, which deliver, through the chains 74, power to the sprockets 75, 75, mounted on the cross shaft 76. Concentrically mounted with the sprockets 75 are smaller sprockets 77, 77, which deliver power, through chains 78, 78, to the sprockets 69. The ratio of the gears 44, 45, the size of the sprockets 73, 75, 77 and 95 69, the speed of the motor, and the reduction obtained by the primary drive, are all chosen to secure proper correlation of movement in the apparatus.

A conveyor system formed of a series of 100 chains runs from the rear to the front of the machine carrying shingles to the front. This conveyor is composed of chains 35, 35, etc., working over the sprockets 36, 37, which are supported by the shafts 38, 39, journaled in 105 pillow blocks 41, 42, mounted upon the base 11. A series of longitudinal hardwood bars 43, 43, etc., lie directly beneath the chains affording them support.

The cam 83 carries upon its face a complex 110 slot 93, in which rides a pin 94, attached to the arm 95 which is pivoted at a point 96 and at its further extremity 97 also pivoted to the vertical rack 98. When the cam 83 revolves, therefore, the rack 98 is driven up and down. The rack 98 engages with a gear 99, mounted upon a transverse shaft 101, so that vertical movement of the rack causes the shaft to revolve. The rack is kept in engagement with the gear 99 by means of the yoke 102 115 and a roller 103 carried by the yoke. The shaft 101 carries a series of right angle shaped arms 104, 104, placed intermediately between the carrier chains 35, as illustrated. When the cam 83 revolves, therefore, the intermediate linkage will cause the right angle arms to pick up whatever shingles may have been carried to them by the carrier chains, swing them through 180° of arc, and drop them upon the roller carrier 105. Carrier 120 125 130

chains 35 are driven through the intermediary of a sprocket 106, located upon the shaft 76, and a connecting chain 107 driving the sprocket 108, mounted upon the shaft 39. The cam 83 is carried upon a short jack shaft 109, upon which is mounted a sprocket 111, which is driven through the chain 112 by a sprocket 113 located upon the shaft 76.

The organization for preventing the shingles from sticking and jamming is as follows:— A crank 81, pivoted at 79 upon an upwardly extending portion of the support 12, carries at its extremity a roller 82, which bears upon the face of a cam 83. The upper end of the crank is pivoted at 84 to a longitudinal bar 85. A like bar 88, carried on the pivoted supporting members 80, 80, is located at the other side of the machine.

Extending between these two parallel bars, and located immediately in front of the stop members 23, is a series of cross rods 87, which are affixed to the parallel bars. The cross rods carry in their length a series of hammers 86, which engage with the flexible members 29 of the stop system. Since the bars are free to swing slightly horizontally, the hammers hit the spring stop members 29 whenever the sharp projection 92 of the cam 83 passes under the roller 82. The stop bars 29 are immediately restored to their proper position by the pull of the spring 33 exerted against the stop frame element 27 and the cap of the bolt 32, which is attached to the hinged stop bar.

The operation of the device is as follows:— The revolution of the shaft 13 causes, through the appropriate driving intermediaries, the engaging blocks 53 to be forced forwardly through the slots in the table 21. The block 53, therefore, causes the bottom shingle of the bundle 22 to be forced out from under the stop member 29. The revolution of the appropriate cross shafts 76, 68, etc., causes the cam 67 to revolve and the arm 71 to move up and down following the contour of the cam. For each one-half revolution of the chain carrying the engaging blocks 53, the cam 67 turns through one-fifth of a revolution. Accordingly, through the appropriate mechanism, the table raising and lowering shaft 64 is turned, and the table linked thereto is raised or lowered depending upon the particular block 60, 70, etc., which is presented by the cam face at the time.

In the organization of the machine as described, when the table is dropped to its lowest possible position and the stop member 29 is raised to its highest adjustment, three shingles may be forced out from under the stop 29. As illustrated in Fig. 2, the block 60 applied to the cam face will allow no shingles to be forced out from under. Block 70 will allow one shingle to be forced out and the space 114 on the cam face, which is unprovided with a block, allows three shingles to

be forced out onto the carrier. The carrier chains 35 then receive the shingles which drop onto them from above. These chains are in continuous movement throughout the operation of the machine. The shingles then bring up against the part 115 of the throw-over arms 104. The arms, as before described, are forced through 180°, picking up the shingles from the chains 35 and dropping them on the roller conveyor 105. The shingles are deposited upon the conveyor with the under surface, as the shingles lie upon the chains, uppermost.

The function of the arms 81, the hammers 86, and the hinged stop member 31, etc., is as follows:— As the cam 83 revolves the sharp projection 92 hits the roller 82, causing the arm 81 to be thrust backward violently. The hammers 86 then strike a sharp blow on the stop members 29, which may yield slightly, and are instantly retracted to their normal position by the springs 32, pulling them against the stop bar 27. The stack of shingles, therefore, receives a considerable jolt before the next shingle is to be thrust forth. Sticking or jamming under the gate is accordingly obviated.

It is understood that the positioning of the blocks applied to the face of the cam 67 is the controlling factor in the shingle mixing machine, and that since all operations occur in timed relation unit 1 may deposit none, one, two or three shingles of one color upon the carrier; unit 2 may deposit three, two, one or no shingles of a different color upon the carrier; units 3, 4 and 5 will duplicate the performance. The stack of mixed shingles which is built up upon the carrier 105, therefore, will contain as desired shingles of various colors in color sequence, or groups of shingles of the same color, up to three, which is then broken by some other color. If five units comprise my machine it may be seen that the variegation of color, or the multiplicity of patterns which my machine will produce, is in excess of two hundred different combinations.

But this preferred embodiment is here used for an illustration of the invention, and not to limit the claims appended hereto.

I claim as my invention—

1. In a machine of the class described, a plurality of supports each adapted to hold a stack of like shingles, a carrier, means for removing a shingle from each stack and to deposit it upon the carrier, and means to remove the individual shingles upon the carrier and to pile them in an assorted stack.

2. In a machine of the class described, a plurality of supports each adapted to hold a stack of like shingles, a moving carrier, means for transferring individual shingles from the several stacks successively to the carrier, and means for removing the shingles from the

carrier and stacking them in the order of their deposit on the carrier.

3. In a machine of the class described, a plurality of supports each adapted to hold a stack of like shingles, a carrier, means for removing a shingle from the several stacks successively at selected intervals and depositing them on the carrier in a predetermined order, and means for collecting the shingles from the carrier into an assorted stack.

4. In a machine of the class described, a plurality of supports arranged in series each adapted to hold a stack of like shingles, controlled means for extracting an adjustable number of shingles from the bottom of each stack at timed intervals, means to determine when and how many shingles shall be so extracted, and means for grouping each set of extracted shingles in an assorted stack.

20 5. In a machine of the class described, a plurality of supports each adapted to hold a stack of like shingles differing from those in the other, means varying in a predetermined manner throughout each cycle of operation controlling means for removing an adjustable number of shingles from each stack at regular intervals, and means for delivering the removed shingles for each interval in regular sequence into an assorted stack.

30 6. In a shingle mixing machine, a table, a stop gate, means cooperating with slots in the table to force sheets of material stacked thereon out and under said stop gate, means for raising and lowering said table to predetermined heights in predetermined sequence, and means for carrying shingles away after they have been forced out under said gate.

40 7. In a device of the class described, a plurality of units adapted to eject sheets of material, a movable carrier receiving sheets thus ejected, and pickup means at the end of said carrier adapted to lift and stack such sheets in the order of their deposit upon said carrier.

45 8. In a shingle mixing machine, a moving carrier, stacks of shingles positioned thereover, means causing shingles to be released from said stacks and to drop on said carrier in a predetermined manner, and means for removing said shingles from said carrier.

50 9. In a machine of the class described, a plurality of tables supporting stacks of shingles, the shingles in each stack being alike but differing in physical appearance from the shingles in the other stacks, said tables being adapted to be raised and lowered in a predetermined manner, a plurality of fingers adapted to engage the lower shingles of said stacks, means for causing the fingers to travel transversely across the stack thereby displacing the lowermost shingles, adjustable stop means to prevent the whole stack 55 from being displaced, and means determin-

ing the vertical position of the supporting tables.

10. In a device of the class described, means supporting a plurality of stacks of shingles, means acting in timed relation to deliver shingles from said stacks to a carrier the progress of which is in timed relation to the delivery of shingles thereto, takeoff means at one end of the carrier operating in timed relation to remove shingles therefrom, and stacking means for piling said shingles in the order in which they were delivered to the carrier.

11. In a shingle mixing device, a table capable of vertical movement, the vertical position of said table being determined by a cam and cooperating parts, and means provided for changing the contour of the cam whereby the vertical position of the table in relation to the angular position of the cam may be controlled.

12. In a shingle mixing device, a plurality of tables each capable of vertical movement, the vertical position of the tables being separately determined, an individual cam and cooperating parts, each of said cams operating in timed relation one with the other, and means provided for changing the contour of the cam whereby the vertical position of the table in relation to the angular position of the cam may be controlled.

13. In a shingle mixing device, a supporting structure, a plurality of slotted tables mounted thereon, a plurality of stop gates mounted on said structure and immediately associated with each of the tables preventing the lateral displacement of material stacked on the tables, certain elements of said stop gates being vertically adjustable with respect to said tables whereby adjustment to the varying thickness of shingles is secured.

14. In a device of the class described, a rotatable cylindrical drum, cam members affixed to the periphery of the drum, said cam members being detachable and of different thicknesses whereby a cam of variable contour serving to control the operation of the device is formed.

15. In a device of the class described including a table, a stop gate, a stack of shingles on said table, means for imparting a blow to said stop gate and therethrough to said stack of shingles, whereby the stack is jolted and sticking or jamming is prevented.

16. In a shingle mixing machine, a stop gate, means to support a stack of shingles, means to remove a shingle from the stack and to force it under the stop gate, means for raising and lowering one of the above means to predetermined heights in predetermined sequence, and a carrier for removing the shingles after they have been forced out under the gate.

17. In a shingle mixing device, means

adapted to support a stack of shingles, means for removing a shingle or shingles from said stack, a cam and cooperating parts arranged to determine the vertical position of one of the above means, and apparatus for changing the contour of the cam whereby the vertical position of the means in relation to the angular position of the cam may be controlled and the number of shingles removed determined.

18. In a machine of the class described, in combination, a plurality of supports for stacks of shingles, means for removing shingles from the supports successively, means for assembling the removed shingles in a single stack and in the order of their removal from the several supports, means for regulating the order of removal from the several supports, and means for variably determining the number of shingles removed from each support at each action.

19. In a machine of the class described, a plurality of fixed supports each adapted to hold a stack of like shingles, a carrier, an ejector vertically adjustable to engage a predetermined number of the lowermost shingles of each stack and to deposit them upon the carrier, and means continuously controlling the vertical position of the ejector.

20. In a shingle mixing machine, a table, ejecting means cooperable with said table, the vertical position of which is determined by a cam and cooperating parts, and means provided for changing the contour of the cam whereby the vertical position of the ejecting means with respect to the angular position of the cam may be controlled.

21. In a device of the class described, means supporting a plurality of stacks of shingles, ejecting means acting in timed relation to deliver shingles from said stacks to a carrier, the progress of which is in timed relation to the delivery of shingles thereto, take-off and stacking means at one end of the carrier operating in timed relation to the ejecting means.

22. In a shingle mixing machine, means for supporting a plurality of stacks of shingles thereon, the shingles of the several stacks having different characteristics, means for removing the shingles from said stacks in a predetermined order, and means for stacking the removed shingles in a common pile and in the order of their removal from the primary stacks.

In testimony whereof I affix my signature.
ALBERT E. F. MOONE.
